(57) **CLAIM**

The ornamental design for a golf ball teeing device, as shown and described.

DESCRIPTION

FIG. 1 is a perspective view of a golf ball teeing device embodying my new design, showing the design in use for teeing a golf ball;

FIG. 2 is a perspective view thereof shown without the environmental, in use disclosure in FIG. 1;

FIG. 3 is rear perspective view thereof;

FIG. 4 is a front view thereof;

FIG. 5 is a rear view thereof;

FIG. 6 is a top view thereof;

FIG. 7 is a bottom view thereof; and,

FIG. 8 is a right side view thereof.

The broken lines depicting portions of the golf ball teeing device and its environment are for illustrative purposes only and form no part of the claimed invention.

1 Claim, 7 Drawing Sheets
